UNITED STATES PATENT OFFICE.

ALFRED L. EUSTICE, OF CHICAGO, ILLINOIS.

SAFETY-FUSE.

1,400,480.

Specification of Letters Patent.

Patented Dec. 13, 1921.

Application filed March 7, 1918. Serial No. 220,961.

To all whom it may concern:

Be it known that I, ALFRED L. EUSTICE, a citizen of the United States, and resident of Chicago, in the county of Cook and State 5 of Illinois, have invented certain new and useful Improvements in Safety-Fuses, of which the following is a specification.

This invention relates to inclosed fuses, or more strictly speaking to safety fuses.

10 One of the objects of this invention is to prevent reckless repair of safety fuses after the fusible element has melted, or to prevent substitution of the fusible element.

Another object is to provide a simple and 15 compact safety fuse of the non-renewable type adapted to meet the various requirements for successful commercial use.

Generally speaking these and other objects are accomplished by providing a 20 safety fuse having in combination, a closed casing, a fusible element mounted therein and electrically connected to parts exterior of the casing, and deflecting means to prevent the introduction of a substitute for the 25 fusible element.

The invention is illustrated on the accompanying sheet of drawings, in which,

Figure 1 is a longitudinal sectional view 30 of a fuse embodying my invention;

Fig. 2 is a transverse sectional view taken in the plane of line 2—2 of Fig. 1;

Fig. 3 is a longitudinal sectional view of the same fuse taken at right angles to the section shown in Fig. 1;

35 Fig. 4 is a sectional view taken in the plane of line 4—4 of Fig. 3;

Fig. 5 is a longitudinal sectional view of a fuse embodying a modification of my invention, and

40 Fig. 6 is a transverse sectional view taken in the plane of line 6—6 of Fig. 5.

The various novel features of my invention will be apparent from the following description and drawings and will be particularly pointed out in the appended 45 claims.

As is well known, a fuse is placed in a circuit to protect that circuit and also to protect instruments or devices connected in 50 the circuit. The fuse is designed to carry a certain load and when that load is exceeded, the fuse melts requiring a new fuse to be placed in the circuit. It is not uncommon among some people to attempt to 55 substitute for the fusible element by insert-

ing another fuse of different capacity or even substitute a nail thereby defeating the very purpose of a safety fuse.

By means of my fuse construction, I prevent any unnoticed substitution of the fusible element, thereby requiring the use of a new fuse when the fusible element of the one in service has been melted.

To this end I have provided a fuse including a cylindrical non-conducting shell 65 10, the ends of which are covered by caps 11 of conducting material, the shell and caps forming a closed casing. Electrically connected to the caps 11 and extending through the shell 10 are spaced terminal straps 12 70 to which ends of the fusible element 13 are connected by screws 14 or by any other suitable means. It is apparent that if the fuse thus far described is inserted between terminal clips so that the metal caps 11 engage the terminal clips, the electric circuit will be completed between the clips by fusible element 13. If for any reason the circuit becomes overloaded a certain predetermined amount, the safety fusible element 13 will 75 80 melt thereby protecting the circuit and devices connected therein. It is under such conditions that attempts are made to substitute for the fusible element instead of using a new fuse.

To prevent substitution of the 85 fusible element 13, I have inclosed within the shell 10 at the ends thereof, or more strictly speaking intermediate the ends of the caps 11 and the terminal straps 12, deflecting means 15, which, as shown in Figs. 90 1 to 4, inclusive, are in the form of hardened steel disks. Preferably these steel disks are embedded in asbestos 16 or any other suitable insulating material which preferably is somewhat flexible or will permit the disk to 95 vary its normal position. By means of this arrangement it will be extremely difficult if not impossible for one to drive a nail longitudinally through the fuse structure to connect the terminal straps 12 or otherwise 100 substitute for the fusible element originally in the fuse casing, and as a matter of fact if anyone should tamper with the fuse by attempting to substitute for the fusible element, the same would be observed readily, 105 for the external parts of the fuse would be considerably damaged thereby giving notice that an attempt had been made to substitute for the original fusible element. In any event, it would be quite impossible to drive 110

a nail through or around the deflecting disks 15 or to drill a hole therethrough in an effort to substitute for the fusible element.

- 5 Referring to Figs. 5 and 6 of the drawings, it will be noted that instead of using a flat hardened steel disk 15, I have provided deflecting means in the form of semispherical members 17 which are located intermediate 10 the caps 18 and the terminal straps 19, said deflecting members preferably being packed in asbestos or similar non-conducting material. It is apparent that it would be impossible to drive a nail through this deflecting 15 means or drill a hole in same for the purpose of substituting a fusible element for the one originally placed within the casing.

By means of the arrangement herein disclosed, a safety fuse of the non-renewable 20 type is provided which is adapted to meet the various requirements for successful commercial use.

It is my intention to cover modifications 25 of the invention which fall within the spirit and scope of the following claims.

I claim:

1. A safety fuse having in combination, a closed casing, a fusible element therein electrically connected to parts exterior of the 30 casing, and deflecting means contained within said casing and adapted to deflect any axially entering element from axial penetration of the fuse.
2. A safety fuse having in combination, a 35 closed casing, a fusible element therein electrically connected to parts exterior of the

casing, and deflecting means yieldingly supported within said casing and adapted to deflect any axially entering element from axial penetration of the fuse.

40

3. A safety fuse having in combination, a casing, conducting caps inclosing the ends thereof, conducting members within the casing electrically connected to said caps, a fusible element connecting said conducting members, and deflecting means interposed between said caps and conducting members for preventing the passage of a substitution of the fusible element by lateral deflection thereof.

45

4. A safety fuse having in combination, a closed casing, a fusible element mounted therein and electrically connected exteriorly, and impenetrable deflecting means yieldingly interposed between said fuse and a 50 portion of the casing to prevent passage of a substitution of the fusible element.

50

5. A safety fuse having in combination, a closed casing, a fusible element mounted therein and electrically connected exteriorly 55 of the casing, non-conducting material within said casing, and deflecting means embedded in said non-conducting material for preventing the substitution of the fusible element.

55

Signed at Chicago, Illinois, this 21st day of February, 1918.

ALFRED L. EUSTICE.
